UNITED STATES PATENT OFFICE.

THOMAS FORSTNER, OF NEW ULM, MINNESOTA.

CORN-BIN.

1,045,963.

Specification of Letters Patent.

Patented Dec. 3, 1912.

Application filed May 13, 1911. Serial No. 626,976.

To all whom it may concern:

Be it known that I, THOMAS FORSTNER, a citizen of the United States, residing at New Ulm, in the county of Brown and State of Minnesota, have invented certain new and useful Improvements in Corn-Bins, of which the following is a specification, reference being had therein to the accompanying drawing.

10 This invention relates to storage buildings, such, for instance, as sheds or bins for storing corn or other material, and the principal object of the same is to provide simple means for thoroughly ventilating the building, and also to provide means for preventing moisture obtaining access to the interior of the said building.

Preferred and practical embodiments of the invention are shown in the accompanying drawing wherein:

Figure 1 is a view in side elevation of a storage building constructed in accordance with this invention. Fig. 2 is a transverse sectional view thereof. Fig. 3 is a detail fragmentary perspective view of a portion of one of the sheathing plates. Fig. 4 is a similar view of a variation of the invention.

The improved storage building has been shown as a shed or bin for storing corn and other perishable material and includes a base or floor 5 carrying the vertical studding members 6, the upper ends of which are connected by the longitudinal beams 7. The end studding members are connected 35 by the transverse beams 8. The base 5 studding members 6 and beams 7 and 8 form a frame upon which the roof 9 is mounted. The roof and frame are, of course, showings of but one of the many types that may be 40 used in connection with this invention.

The frame is sheathed by the plates 10 which are fastened to the studding members 6 and have their meeting edges overlapped.

Said plates are preferably of sheet metal and are stamped, punched, or otherwise treated to provide a plurality of openings 11 for permitting a free circulation of air through the building. The material forced from said plates to provide said openings 11, is concaved and projects downward on an incline to provide shields 12 for said openings that will prevent rain, snow or other moisture passing through said openings and will also shade the same so that the sun will not bleach or otherwise affect the contents of the building.

In the form of the invention shown in Fig. 4 the frame is provided with regularly spaced parallel flat metal bars 13 which are horizontally arranged so that ventilating openings 14 are formed between each bar. Said bars 13 have downwardly inclined shielding plates 15 projecting outwardly from their lower longitudinal edges, said plates 15 overhanging the opening 14 to prevent moisture and the same rays passing therethrough.

In both forms of the invention it will be clear that this invention provides simple means for thoroughly ventilating the building and at the same time preventing moisture or sun obtaining access thereto.

What I claim as my invention is:

A storage building comprising a frame, and sheet metal sheathing plates therefor provided with air admitting openings and outwardly-projecting downwardly-inclined spherocconcave shields overlapping said openings in spaced relation.

In testimony whereof I hereunto affix my signature in presence of two witnesses.

THOMAS FORSTNER.
